L. S. SISSON, OF WEST EDMESTON, NEW YORK.

Letters Patent No. 85,034, dated December 15, 1868; antedated December 5, 1868.

IMPROVED CAR-BRAKE.

The Schedule referred to in these Letters Patent and making part of the same.

To all whom it may concern:

Be it known that I, L. S. SISSON, of West Edmeston, in the county of Otsego, and State of New York, have invented certain new and useful Improvements in Car-Brakes; and I do hereby declare that the following is a full, clear, and exact description thereof, reference being had to the accompanying drawings, and to the letters of reference marked thereon, which form a part of this specification, in which—

Figure 1 is a view in perspective of a portion of a railroad-car, with my improvement attached.

Figure 2, a view of the guide in which the end of the lever that throws the apparatus into operation moves.

Figure 3, a view of the guide for the lever which takes off the brakes.

The object of my invention is to provide a suitable arrangement of devices for utilizing the motion of a car, to put on the brakes, and stop the same, when required, either in case of accident, or in the ordinary working of the train; and to this end,

My improvement consists in connecting a cam upon one of the axles with a cam-rod, which rotates the brake-shaft in such manner that, by a single movement of a lever, the brakes will be automatically applied to the wheels by the revolutions of the axle, and a movement of another lever instantaneously takes them off.

In the accompanying drawings, which represent a convenient arrangement of parts for carrying out the object of my invention,

A A represent portions of a car-truck, and

B, the axle, upon which are secured the wheels b b.

A cam, B', is attached to this axle, at any suitable point between the wheels, and is provided with a friction-roller on its wearing-surface.

A cam-rod, C, is suitably bent at one end, to receive longitudinal motion from the revolutions of the cam B', and pivoted at its other end to a plate, C', upon the brake-shaft F.

It is suspended near the axle in a swinging hanger, c, pivoted to the car-body, so that its end on which the cam-frame is formed can be moved laterally upon the axle, so as to be thrown into or out of gear with the cam B'.

A spring, c', attached to the car-body, presses against the lower end of the hanger c, to hold the cam-rod C in gear with the cam B'.

A bent or elbow-lever, D, is pivoted at its angle to the car-body, and has a spring, d, attached to the same, pressing against one of its arms, and its other arm bearing against a stop on the hanger c.

The effect of this arrangement is to hold the rod C out of gear with the cam B'; the tension of the spring d being greater than that of the spring c', and acting in a contrary direction.

A cord, d', is attached to the lever D, near the end of its longer arm, and, passing over a pulley in the car,

is connected to a cord which runs forward to the locomotive. By raising the end of the lever by a pull upon the cord d', the opposite arm is drawn away from the stop on the hanger c, and the spring c' forces the rod C into gear with the cam.

When the spring d is again allowed to exert its tension upon the lever D, it forces its short arm up against the hanger c, and throws the cam-rod C out of gear with the cam.

The end of the arm of the lever D, to which the cord d' is attached, moves in a guide, D', which is shown on an enlarged scale in fig. 2. Within this guide are pivoted the fingers d² and d³, and spring d⁴.

The finger d² is pivoted at a point somewhat below its centre, and has a recess in its upper part, against which the finger d³ is pressed by the spring d⁴. The lever D is raised by the cord, until it passes the upper point of the finger d², when the cord is released, and it drops into the recess in d², where it is retained by the spring d⁴, and the cam-rod remains in gear with the cam.

To throw these parts out of gear, another pull upon the cord d' is given, which raises the end of D past the point of the spring d⁴, when, the cord being released, the spring d throws the end of D down to the bottom of the guide D', and causes its opposite arm to press against the hanger c, and throw the cam-rod out of gear.

One end of the cam-rod C is pivoted to the oscillating plate C', which moves freely upon the brake-shaft F.

A plate, f², is pivoted to the top of C', to which a pawl or dog, f¹, is attached.

A ratchet, f, is secured upon the brake-shaft, in the teeth of which the pawl f¹ engages, to impart rotation to the shaft.

A plate, E², is pivoted to the bearing of the brake-shaft, having upon it a pawl, e³, to hold the brake-shaft stationary, when the pawl f¹ is drawn out of contact with the teeth of the ratchet f. The plates E² and f² are connected by a suitable joint.

One tooth of the ratchet is cut away, leaving a dead-space, x, over which the pawl f¹ moves, without imparting motion to the shaft F.

A lever, E, is connected to the plate E² at one end, and to a cord, e, at its other end, being pivoted to the car-body between them. The cord e passes up over a pulley into the car, and is connected with a cord passing longitudinally therein.

The end of the lever moves vertically in a guide, E, shown on an enlarged scale in fig. 3. It is pressed down by a spring, e', and held in position by a catch, e, pivoted to its end, which catch serves as a point of attachment for the cord e'.

When the lever E is in the position shown by the drawings, the catch e rests in an offset, at the bottom of the guide E, and is held in position by the spring e'

The pull upon the cord e^1 brings the catch e to a perpendicular position, and enables the lever E to be raised, to withdraw the pawls e^3 and f^1 from the ratchet f .

The cord f^3 , which operates the brakes, is attached to the shaft F , and, at its opposite end, to a spring, g , which unrolls it from the shaft when the brakes are to be taken off.

The operation of the devices is as follows:

The parts being in the position shown by the drawing, and it being desired to put on the brakes, a single pull is given to the cord d^1 , which, as before explained, throws the cam-rod C into gear with the cam B' , and imparts rectilineal reciprocating motion to the rod by means of the revolutions of the axle. This rod, being connected to the plates C' and f^2 , and pawl f^1 , causes the latter to rotate the shaft F by means of the ratchet f winding the brake-cord f^3 upon the shaft, and applying the brakes, the shaft being prevented from retrograding by the pawl e^3 .

When the brakes are brought down sufficiently hard, the dead-space x is arranged to be opposite the pawl, and the shaft F receives no further movement, whether the cam-rod is in gear or not. It is preferable, however, to throw it out of gear by giving another pull upon the cord d^1 , as soon as it is ascertained that the brakes are down.

When the train has been brought to a stand, and the brakes are to be taken off, the lever E^2 is raised by pulling upon the cord e^1 , which withdraws the pawls

f^1 and e^3 from the ratchet f , and the spring g unrolls the cord f^3 from the shaft, and takes off the brakes.

From an examination of the parts, it will be seen that the devices will operate equally well when the car is running in either direction, and the cords d^1 and e^1 may be attached to any points of the train found most convenient.

The severing of the cord d^1 by the breaking of the couplings, will immediately cause the brakes to be applied, thus bringing a means of safety into requisition on the first intimation of danger.

Having thus fully described my invention,

What I claim therein as new, and desire to secure by Letters Patent, is—

1. The combination of the pivoted hanger e , lever D , and springs c^1 and d , with the cam-rod C , for the purpose of throwing the same into and out of gear, as set forth.

2. The guide E^1 and catch e , for governing the position and movements of the lever E , as set forth.

3. The guide D' , with its fingers d^2 and d^3 , and spring d^4 , arranged and operating as and for the purpose described.

In testimony that I claim the foregoing as my own, I affix my signature, in presence of two witnesses.

L. S. SISSON.
